ABSORBENT AND VENTILATED BOOT AND
SHOE PRESERVERLeo F. Badoux and Charles Benjamin Pfaff,
Detroit, Mich.

Application September 18, 1933, Serial No. 689,980

8 Claims. (Cl. 12—128.1)

The object of our invention is to provide a novel and efficient absorbent and ventilated boot and shoe preserver, perforated or channeled in such a manner as to allow air circulation while inserted 5 in the boot or shoe, and also suitably constructed to hold a material that will at the same time be absorbent and act as a deodorant, whereby to absorb the perspiration and function to destroy offensive odors. It is also an object of our invention to provide a construction that will permit 10 of convenient renewal of the absorbent material without harm to the boot and shoe preserver, to provide means for inserting the absorbent material either within or exterior to an inner shell; 15 and to provide the novel combination and arrangement of parts disclosed in the accompanying drawings. We attain these and other objects of our invention by the mechanism illustrated in the drawings, in which—

20 Figure 1 is a top plan of the invention in the form of a shoe tree;

Fig. 2 is a longitudinal vertical section of same on line 2—2 of Fig. 1;

Fig. 3 is a perspective view of the invention;

25 Fig. 4 is a transverse section on line 4—4 of Fig. 1;

Fig. 5 is a transverse section on line 5—5 of Fig. 1;

Fig. 6 is a transverse section on line 6—6 of

30 Fig. 2; and

Fig. 7 is a transverse section on line 7—7 of Fig. 2.

Like numerals designate like parts in each of the several views.

35 Referring to the accompanying drawings, we provide a connecting rod 1 pivotally connected at its forward end by a suitable rivet or bolt 2 to the brackets 3, integral with or affixed to the front outer shell 22. We provide a bolt 5 extending 40 through aperture 4 in connecting rod 1 and sleeve 8 and the forward end of links 6 to provide a central hinge between links 6 and members 1 and 8. We provide a bolt or rivet 7 pivotally connecting the rear ends of links 6 with tongues 17 or the 45 heel member of the boot or shoe tree. We provide a sleeve 8 in which connecting rod 1 is slidably adjustable. We provide a ring 9 preferably integral with sleeve 8 and functioning as a means for removing the tree from the boot or shoe. As

50 shown in Fig. 2, we provide an adjusting spring 12 secured by suitable rivet or screw 13 to the bottom portion 10 of the sleeve 8 and having its upturned end 14 projecting through a slot 11 and releasably engageable in the rack portion 15 of connecting bar 1.

We provide a finger piece 16 suitably attached to the free end of adjusting spring 11 for withdrawing same from engagement with the rack 15.

We provide a heel outer shell 18 having an opening 19 in the top portion and a heel inner shell 20 60 on which is removably placed suitable absorbent material 21. We provide a front outer shell 22 within which is contained a front inner shell 23 adapted to hold suitable absorbent material 24. It is to be understood that the absorbent material 65 may be placed in the space between members 18 and 20, and between members 22 and 23; or within members 20 and 23, as shown, or both.

The outer shell 22 is provided with a bottom flange 25 which functions as a skeleton sole for 70 the boot or shoe tree. Both the front of the shell 22 and the heel outer shell 18 are provided with spaced narrow panels 26 and spaced wide panels 27, with spaces or channels between the aforesaid panels and designated 29. Each of the 75 wide panels 27 are provided with longitudinal depressions which function as spacing elements to space the outer shells 22 and 18 from the respective inner shells 23 and 20. The space intervening between the front outer shell 22 and the front inner shell 23 is designated 30 and the corresponding space between the heel outer shell 18 and the heel inner shell 21 is designated 31.

The spaces 29 in the front outer shell 22 and in the heel outer shell 18 permit of circulation of air 85 around the front inner shell 23 and the heel inner shell 20 as the respective inner and outer shells both of the front portion of the shoe tree and the heel portion of the shoe tree are kept in a spaced relation by the depressions 28 in the wide 90 panels 27, as shown in Figs. 4, 5 and 6 of the drawings. The front inner shell 23 and the heel inner shell 20 are each covered or filled with suitable absorbent material. This absorbent material absorbs all perspiration and destroys any offensive 95 odors.

It will be noted that the front and heel inner shells can readily be removed at the open end and thus permit of convenient removal and renewal of the absorbent material whenever desired. The front portion of the boot and shoe tree and the rear portion are pivotally connected by the connecting rod 1, sleeve 8, and links 6, which have the pivot connections 2, 5 and 7, as illustrated in Fig. 3.

3. The boot and shoe tree is adjustable by means 105 of the adjusting spring 12, the upturned end of which releasably engages in the rack portion 15 of connecting rod 1, as shown in Fig. 2. The ring 9 provides a convenient means for expanding the shoe tree or contracting it for removal of the 110

shoe. The inner shells 20 and 23 are filled or covered with absorbent material. In consequence the device will help materially in preserving the leather and prolonging the life of the shoe.

5 With very little change in construction our device can be adapted to riding boots as well as shoes, by simply having a part to fit the leg of the boot, and preferably being made in three sections and fitting over the top of the shoe tree 10 with a spring hook to connect with the ring for withdrawing the tree from the shoe.

The absorbent material described is impregnated with a suitable chemical or chemicals to act as a deodorant without harming the lining or 15 leather of the shoe or boot to which the device is applied.

What we claim is:

1. In a boot and shoe preserver, the combination of an outer shell comprising a series of integrally connected but spaced panels, some of the panels having depressions adapted to function as an inner spacing element, an inner shell mounted within said outer shell and spaced therefrom by the aforesaid depressions, and absorbent material 25 mounted on the inner shell.

2. In a boot and shoe tree, the combination of an outer shell comprising a series of integrally connected but spaced panels, some of the panels having depressions adapted to function as an inner spacing element, an inner shell mounted within said outer shell and spaced therefrom by the aforesaid depressions, and absorbent material mounted on and within the inner shell.

3. In an absorbent and ventilated boot and shoe tree of the type described, the combination of an inner shell, absorbent material removably mounted in the inner shell, an outer shell encircling the inner shell, said outer shell comprising a series of panels and spaces therebetween for ventilation, 40 and means on the outer shell for spacing same from the inner shell.

4. In a ventilated and absorbent boot and shoe preserver, the combination of an inner front shell, absorbent material mounted in said shell, an outer front shell enclosing said inner shell, means on the outer shell for spacing same from the inner shell to permit circulation of air therebetween, the outer shell having spaces for circulation of air therethrough, an inner heel shell, absorbent material mounted in the heel shell, an outer heel shell spaced from the inner shell, means for circulation of air through the outer shell and between the outer and inner shells, and means linking the front outer shell to the heel outer shell.

5. In combination with the mechanism defined in claim 4, means for adjusting the length of said linking mechanism.

6. In combination with the mechanism defined in claim 4, means for adjusting the length of said linking mechanism, and a ring for raising and lowering the central hinge portion of the link mechanism to contract or expand the boot and shoe preserver.

7. In a boot and shoe preserver, the combination of an outer shell comprising a series of integrally connected but spaced panels, some of the panels having longitudinally extending depressions adapted to function as an inner spacing element, an inner shell mounted within said outer shell and spaced therefrom by the aforesaid depressions, and absorbent material mounted in the inner shell, said material being impregnated with a deodorant.

8. In a boot and shoe preserver, the combination of an outer shell comprising a series of integrally connected but spaced panels, some of the panels having depressions adapted to function as an inner spacing element, an inner shell mounted within said outer shell and spaced therefrom by the aforesaid depressions.
